UNITED STATES PATENT OFFICE.

EDGAR A. WANGERSHEIM, OF CHICAGO, ILLINOIS.

DESIGN FOR A LIGHTING FIXTURE.

Application filed October 5, 1923. Serial No. 7,411. Term of patent 3½ years.

To all whom it may concern:

Be it known that I, EDGAR A. WANGERSHEIM, a citizen of the United States, residing at Chicago, in the county of Cook and State of Illinois, have invented a new, original, and ornamental Design for a Lighting Fixture, of which the following is a specification, reference being had to the accompanying drawing, forming part thereof.

The figure is an elevational view of a lighting fixture, showing my new design.

I claim:

The ornamental design for a lighting fixture, as shown.

EDGAR A. WANGERSHEIM.
